UNITED STATES PATENT OFFICE.

GEORGE T. BECKNELL, OF NEVADA, TEXAS.

GIN ATTACHMENT FOR BOLLY COTTON.

1,242,126.

Specification of Letters Patent.

Patented Oct. 9, 1917.

Application filed February 9, 1916. Serial No. 77,252.

To all whom it may concern:

Be it known that I, GEORGE T. BECKNELL, citizen of the United States, residing at Nevada, Collin county, Texas, have invented 5 certain new and useful Improvements in Gin Attachments for Bolly Cotton, of which the following is a specification.

This invention relates in general to uses 10 of gin machinery, and is adapted to be combined with the present form of gin stand and operate in unison therewith.

The invention discloses a form of attachment for gin stands, designed and purposely conceived for exercising an automatic control over the gin stand feeder, and for a 15 similar control in disposing of the hulls and waste product from the gin.

In the operation of the present form of 20 gin machinery it is necessary when the said machinery is used in ginning bolly cotton, which cotton is that harvested late in the season when many bolls and some trash and other foreign waste product is found in the cotton, to provide a gin hand or man attendant to closely watch the gin stand, and 25 at regular periods and intervals serve the machine by closing the gin feed spout door which closes the cotton from the gin stand, and opening the hollow breast door, which 30 opening of the last mentioned door allows the waste products of cotton to be precipitated from the gin stand.

The present invention disclosed in the 35 unified attachment for operation in connection with gin stand eliminates the necessity for providing such attendant as would be otherwise necessary.

With the above and other objects in view, 40 the invention has relation to a certain arrangement and combination of parts, an example of which is described in the following specifications, pointed out in the appended claims, and illustrated in the accompanying drawings, wherein:

45 Figure 1 illustrates said attachment in side elevation.

Fig. 2 illustrates a gin in side elevation, parts of which are shown in section, with 50 parts of the correlated attachment shown in connection therewith.

Fig. 3 is a detailed view of an element of the invention.

Fig. 4 shows the invention attached to a gin stand and illustrates a simple form of gin stand with which said attachment may be correlated.

Fig. 5 illustrates a front elevation of the invention attached to a gin stand.

Referring now more in particular to the drawings, wherein the same reference numerals are used to indicate identical parts, the numerals 1 and 2 indicate the standard or frame supports for the gin stand. Numeral 3 in general points out the gin stand. Numeral 4 indicates the exposed forward cutting edge of the gin saw cylinder. The usual form of huller breast is illustrated in connection with the gin stand, the said huller breast being that portion of the gin stand which is adapted to receive the cotton 65 from a spout 6 and pass same rearwardly through the gin stand 3. The usual form of picker roller 7 is journaled in the huller breast and adapted to pass the cotton into the saw cylinder. The usual form of 70 seed spout 6 is shown, which said seed spout is adapted to receive the seed precipitated downwardly from the picker roller and upon the saw cylinder as indicated by the arrow A in Fig. 4.

The gin stand is provided with the usual form of huller breast door 8, which member is a depending door having an arcuate form symmetrical in form to the picker roller 6 and spaced apart therefrom, said member 85 being pivoted at its upper edge upon a transverse shaft 9. The cotton feed chute 6 is provided with a flap door or valve 10 depending from and hinged to a transverse shaft 11.

In the operation of the present form of 90 gin machinery, a simple example of which present form of gin machinery has been above given, the cotton passes from its originating source into the spout 6 and gradually passes downwardly through the opening 12 95 in the huller breast upon the picker roller and there the ginning action is perfected whereby the seed and lint are separated. The said gin stand requires the constant attention of an attendant to regularly open 100 and close the valve 10, thereby shutting off the flow of cotton and subjecting the door 8 to an outward pull, which frees and releases the bolls and other waste products

from its compressed form in and about the picker roller, allowing said waste products to be precipitated downwardly into a boll conveyor 13.

5 In the application of the present invention to the gin machinery, the above described attendant and operation is eliminated.

10 Reference is now had to Figs. 1, 2 and 3 for a description of the invention, and to Figs. 4 and 5 for a proper association of said invention with the gin machine.

15 The numeral 14 represents an upright standard or frame of substantial strength and sufficient height to carry the assembled elements of the present invention. A substantially large spur wheel gear 15 is journaled upon a stud 15^a which is fixed to the upper portion of the standard. Said gear 20 wheel carries upon the opposite sides thereof rollers 16 and 17 adapted to be retained and revolve upon the pin 17^a, which pin is fixed to the said gear wheel as illustrated in Fig. 3. A support arm member 18 is fixed upon 25 the standard 14 and spaced closely to the gear 15. Said arm member carries on its upper extremity a pinion 19 fixed to a shaft 20. A drive pulley 21 is carried by the shaft 20 and is adapted to drive the large gear 30 through the pinion. A belt 22 is provided for the pulley and adapted to deliver the required power for operating the device. An arm, actuating lever 23 is pivoted upon the support member 18. Said member is mounted 35 upon a pin 24 and has its upper extremity lying adjacent to one side of the gear and in direct path with the roller carried by that side of the gear 15. The lower extremity of the actuating lever 23 is provided with an 40 eye and has a connecting link 25 connected therewith and extending rearwardly where a linked connection is formed with the lower portion of the door member 8, thereby establishing a controlling relation of the member 45 8 by the actuating lever 23.

50 The transverse shaft 11 which supports the flap valve 10 projects beyond the face of the driven member 15 and is provided upon its extremity with a depending actuating member 26. Said member hangs closely adjacent to one side of the driven member 15 and in direct path of the roller 16 carried by the said driven member.

55 The belt 22 delivers the power from a convenient overhead shaft and subjects the large gear member 15 to a slow rotary motion in the direction indicated by the arrow. The members 23 and 26 are adapted to control the opening and closing of the door members 8 and 10 and subject said members to a regularly timed opening and closing action. As the pin 16 approaches the actuating arm 60 26 and comes in contact therewith, the flap valve 10 is raised thereby, allowing a prede-

termined quantity of cotton to be precipitated into the hollow breast, as the pin passes on and beyond the extended length of the member 26 said member will drop into the position illustrated in the drawings, and thereby close the spout 6 from a further delivery of cotton to the gin stand. During 70 the slow revolution of the wheel 15 and before the pin 16 again opens the valve 10, the gin will have completed its ginning action upon the quantity of cotton previously portioned thereto and be ready for the next 75 quantity of cotton.

The roller 17 is so arranged upon the driven member 15 that it comes in operative contact with the actuating lever when the 80 flap door 10 is closed. The roller passes over the face of the actuating lever which subjects the door 8 to a forward action. Such action releases the accumulated bolls and waste products from the huller breast door 85 and instantly cleans the huller breast of hulls and bolls which would otherwise mat and pack in the gin casing and soon begin to whirl with the picker roller.

The controlling members 23 and 26 are so 90 timed as to relieve the gin of any accumulation of bolls, which do not readily drop out of their own accord, just at the time of relieving a new quantity of unginned cotton.

95 Since this machine gives a more regularly timed control over the gin feeder and hull disposer, it is apparent that the cotton, which is harvested in the late part of the season and which at times contains a great quantity of hulls, can be very successfully 100 ginned with a machine equipped with this attachment and have the value of the staple thereby increased.

The invention is presented to include the following claims:

Claims:

1. In a gin attachment for controlling the passage of the cotton through the cotton chute of a gin attachment when bolly cotton is to be ginned, of a shaft, a driven pulley 110 fixed upon the shaft, a driving pinion fixed upon the shaft, a driven member engaging the drive pinion, a roller pin carried near the periphery of the driven member, a closure device located in the cotton chute of 115 the gin stand, a trip device correlated with the closure and adapted to operate said closure when the roller pin carried by the driven member comes in contact with the trip device.

120 2. In a gin attachment for controlling the passage of cotton through the cotton feed chute and for controlling the disposition of the cotton ginned, the combination with a shaft provided with suitable driving means, of a pinion fixed upon the shaft, a gear meshing with and adapted to be driven from the pinion, of a breast door pivoted in the gin

stand at a point forward of the point of ginning, a valve pivoted in the cotton chute, roller pins carried upon the driven gear, a trip device correlated with the breast door, a trip device correlated with the chute valve, the arrangement of the trip devices and the roller pins being such that the trip devices

are brought into operation when they are contacted by the roller pins.

In testimony whereof, I affix my signature 10
in the presence of a witness.

GEORGE T. BECKNELL.

Witness:

CARL O. HAMLIN.
